UNITED STATES PATENT OFFICE

155,886

DESIGN FOR A HANDBAG

Paul Goldberg, Brooklyn, N. Y.

Application April 1, 1949, Serial No. 1,741

Term of patent 7 years

(Cl. D87—3)

To all whom it may concern:

Be it known that I, Paul Goldberg, a citizen of the United States, residing at No. 3042 West 23rd Street, Borough of Brooklyn, in the county of Kings, city and State of New York, have invented a new, original, and ornamental Design for a Handbag, of which the following is a specification, reference being had to the accompanying drawings, forming part thereof.

Figure 4 is a top plan view similar to Figure 3 with the flap in an open position illustrating the two slide fastener closed pockets.

I claim:

The ornamental design for a handbag, substantially as shown.

PAUL GOLDBERG.
